(57) **CLAIM**

The ornamental design for a wall mount, as shown and described.

DESCRIPTION

FIG. 1 is a perspective view of a wall mount, according to a first embodiment of my new design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a sectional view taken along line 8-8 of FIG. 2;

FIG. 9 is a fragmentary sectional view thereof taken along line 9-9 of FIG. 6;

FIG. 10 is a fragmentary perspective view of the wall mount of FIG. 1, shown in an alternate state;

FIG. 11 is a perspective view of the wall mount of FIG. 1, shown in an alternate state;

FIG. 12 is a perspective view thereof, shown in an alternate state;

FIG. 13 is a fragmentary perspective view of a wall mount according to a second embodiment of my new design.

FIG. 14 is a perspective view of the wall mount of FIG. 13, shown in an alternate state;

FIG. 15 is a perspective view thereof, shown in an alternate state; and,

FIG. 16 is a perspective view thereof, shown in an alternate state.

The evenly dashed broken line showing of a wall mount and the dot-dash broken line showing of a vertical slot in FIGS. 13 & 15 is for the purpose of illustrating portions of the article and forms no part of the claimed design.

The remaining dot-dash broken line showing in the figures is for the purpose of illustrating environmental structure and forms no part of the claimed design.
